DESIGN FOR A SWEATER DRIER

Donald C. Grant, Los Angeles, Calif.

Application May 28, 1942, Serial No. 107,034

Term of patent 14 years

To all whom it may concern:

Be it known that I, Donald C. Grant, a citizen of the United States of America, residing at Los Angeles, in the county of Los Angeles, State of California, have invented a new, original, and ornamental Design for a Sweater Drier, of which the following is a specification, reference being had to the accompanying drawing, forming a part thereof.

Fig. 1 is a front elevational view of my sweater drier in compressed position ready for insertion in a sweater,

Fig. 2 is a side elevational view of the sweater drier in the position shown in Fig. 1, and

Fig. 3 is a front elevational view of my sweater drier in the expanded position which it assumes when holding a sweater for drying.

I claim:

The ornamental design for a sweater drier, as shown and described.

DONALD C. GRANT.
